CHRISTIAN A. JAKOBB, OF NEW YORK, N. Y.

WORK-SUPPORT.

1,362,319.

Specification of Letters Patent. Patented Dec. 14, 1920.

Application filed September 25, 1919. Serial No. 326,473.

To all whom it may concern:

Be it known that I, CHRISTIAN A. JAKOBB, a citizen of the United States, and a resident of New York, in the county of Kings 5 and State of New York, have invented certain new and useful Improvements in Work-Supports, of which the following is a specification.

The present invention relates to work-supports for metal- and wood-working machines, such as for instance sawing machines, drilling machines, etc.

The main object of the present invention is to provide a work-support or work-table 15 that may be readily and quickly set at different angles to the tool, for instance a saw or drill.

Another object of the invention is to produce a work-support of the character described, which is adapted for manufacture on a commercial scale, or in other words one which is not so difficult to make as to be beyond the reasonable cost of such a contrivance.

25 A further object of the invention is to devise a work-support of the character mentioned which is simple in construction, efficient in operation, durable in use, convenient to handle and the parts of which may be set, when mounted for instance upon a sawing machine, during the cutting operation, thereby permitting the plane of travel of the work in relation to the line of travel of the saw to be adjusted either step by step 30 or continuously, according to the requirements.

With these and other objects in view, which will more fully appear as the nature of the invention is better understood, the 40 same consists in the combination, arrangement and construction of parts hereinafter described, pointed out in the appended claim and illustrated in the accompanying drawings, it being understood that many 45 changes may be made in the size and proportion of the several parts and details of construction within the scope of the appended claim, without departing from the spirit or sacrificing any of the advantages 50 of the invention.

One of the many possible embodiments of the invention is illustrated in the accompanying drawings, in which:—

Figure 1 is a central, vertical section taken 55 through a work-support constructed in ac-

cordance with the present invention; and Fig. 2 is a top plan view thereof.

In the drawings, the numeral 10 indicates a base, for instance in the form of a table, upon which the work-support is mounted. The work-support comprises two members, denoted by the numerals 11 and 12, the member 11 being stationary, while the member 12 is shiftable in relation to the said first-mentioned member. The member 11 is made in the form of a spherical socket, that is set within an opening 13 in the base plate 10, it being provided with a flange 14 within a recess 15 in the upper face of the said base plate, screws 16 or other fastening means serving to hold the socket in fixed position upon the said base plate. The exposed face of the flange 14 is preferably flush with the upper face of the base plate 10. The member 12 of the support is in the form of a spherical body, that is partly disposed in the socket and adapted to be turned therein. The spherical body 12 is of such dimensions that it projects normally above the base plate 10 and is provided with a flat table portion 18, through which extends an aperture 19. This aperture is centrally disposed on the table portion 18, it being reamed on the underface of the said table portion to permit a tilting of the spherical member 12 in relation to the socket 11 with the tool extending through said aperture. In alignment with the aperture 19, both the spherical member 12 and the socket 11 are provided 80 with large openings 20 and 21, respectively, through which the tool is adapted to extend.

In the drawings a tool in the form of a jig-saw 22 is shown, said saw being stretched in a suitable frame, one element of which, denoted by the numeral 23, is disposed above the base plate 10, while its other element, indicated at 24, is located below the same. This frame may be reciprocated in any suitable manner, the means for reciprocating the same being not shown, as they do not form part of the present invention.

In use, the work is placed upon the table portion 18 upon the spherical member 12, 105 and the latter shifted to present the work at the proper angle in relation to the line of travel of the saw 22. When the table portion 18 of the work-support extends horizontally, the cutting proceeds at right 110

angles to the line of travel of the saw, while when tilted a cut at an oblique angle will be obtained, that is to say a bevel will be formed on the work. The work is usually fed to the saw by hand, and so is also the spherical member 12 held in the desired position.

It is obvious that, while herein the support has been shown in connection with a 10 jig-saw, it may be made use of on drilling machines, etc., just as well.

Attention is also called to the fact that, inasmuch as the spherical member 12 is held in position by hand, the plane of travel 15 of the work may be adjusted in relation to the line of travel of the saw while the cutting operation is being performed, that is to say the said plane of travel may be varied continuously or step by step, as required, or it may be maintained during the 20 entire cutting operation, according to the character of the work to be done.

The work-support herein described is especially suitable for jewelers' use, although 25 not limited thereto. It is particularly adapted for scroll work and knife-edge

work for fine platinum jewelry, wherein the beveling operation requires a continuous change of the plane of travel of the work.

What I claim is:—

In a work-support, the combination with a base plate having an opening and a recess in its upper face around said opening, of a spherical socket set within said opening provided with a flange within said recess, the exposed face of said flange being flush with the upper face of said base plate, and a spherical body partly disposed within said socket projecting normally above said base plate and being provided with a flat table 40 portion, said table portion having a central aperture reamed on the underface of said table portion, said spherical body and said socket having openings larger than said aperture to permit of the passage of a tool 45 therethrough and of an angular shifting of said spherical body in said socket in all directions.

Signed at New York, in the county of New York and State of New York, this 20th 50 day of September, 1919.

CHRISTIAN A. JAKOBB.
